VENTILATING APPARATUS

Friedrich Honerkamp, New York, N. Y., assignor
to Anemostat Corporation of America, a corpora-
tion of Delaware

Application October 4, 1938, Serial No. 233,148

8 Claims. (Cl. 98—40)

This invention relates to ventilating apparatus, and has for its general object to provide, on the one hand, improved valve means for regulating the amount of air delivered from an air supply duct to an air outlet device and, on the other hand, to provide improved means to assure that fresh or treated air delivered from an air duct into a room or other enclosure shall be effectively mixed with the air of the room or other enclosure.

A special object of the invention is to provide a valve means for regulating the amount of air delivered from an air supply duct to an air outlet device, which valve means is of simple, inexpensive construction, is readily and easily installable in an air supply duct, is readily, easily and noiselessly adjustable, and is efficient in the performance of its function.

Another special object of the invention is to provide a simple, practical means which, in itself, insures an efficient intermixing of fresh or treated air supplied from a duct to a room or other enclosure, with the air of the room or other enclosure, even in the absence of an air diffusing outlet device, and which, when used in association with an air diffusing outlet device, insures a much more thorough intermixing of the supplied air with the air of the room or other enclosure than is obtained by use of the air diffusing outlet device alone.

Another special object of the invention is not only to provide an improved valve means for the purpose stated and an improved means as indicated for insuring a highly efficient intermixture of supplied air with the air of a room or other enclosure into which the supplied air is delivered, but to combine said valve means and said air mixing means in a practical unitary structure.

With the foregoing and other objects in view, which will become more fully apparent as the nature of the invention is better understood, the same consists in the novel features of construction, combination and arrangement of parts as will be hereinafter more fully described, illustrated in the accompanying drawing and defined in the appended claims.

In the accompanying drawing, wherein like characters of reference denote corresponding parts in the different views:

Figure 1 is a central, longitudinal section through an air supply duct and an associated air outlet device, illustrating the association therewith of a valve means and an air mixture insur-

ing means in accordance with one practical embodiment of the invention; and

Figure 2 is a horizontal section on the line 2—2 of Fig. 1.

5 Referring to the drawing in detail, A designates, generally, a fresh or treated air supply duct having in a wall 10 thereof an opening 11 through which air is to be delivered from said duct to a room or other enclosure, and B designates, generally, an air outlet device connected with said duct A in air receiving relationship to said opening 11.

While, in accordance with the invention, the use of an air outlet device B is not essential, such a device preferably is employed. Moreover, while an air outlet device B, if used, may be of any known or desired type, the same preferably is of the type shown comprising a plurality of successively larger, open-ended, hollow flaring members 12 disposed in spaced apart relationship to provide a plurality of air distributing passageways therebetween, because it has been found that an air outlet device of this type is highly efficient in dividing the supplied air into a plurality of separate streams of reduced velocity and in thereby causing it to be delivered substantially draftlessly into a room or other enclosure.

In accordance with the invention and regardless of whether an air outlet device B is or is not used, and regardless of the particular construction of such device if same is used, there is provided within the supply duct A suitable means to insure that air flowing from said duct through the opening 11 shall have imparted thereto a motion such as to cause it to become rapidly and thoroughly mixed with the air of a room or other enclosure into which it is delivered. In the present instance this means comprises an auxiliary duct, designated generally as A', formed to

20 40 lead air from the duct A to the opening 11 and to impart to air led from said duct A to said opening 11 a helical or rotary motion. Air passing from the auxiliary duct A' through the opening 11 has a natural motion away from the duct 25 35 45 50 A axially or substantially axially with respect to said opening 11, and this motion of the air, combined with the helical motion imparted thereto by the auxiliary duct A', results in the delivered air partaking of a spiral or cyclonic motion which is particularly effective in causing its rapid and thorough intermixture with the air of a room or other enclosure into which it is delivered.

In order that the auxiliary duct A' may accomplish its intended function of imparting a helical motion to air led by the same to the opening 11,

said duct is constructed to provide within the main duct A a chamber a having a closed substantially semi-cylindrical rear end portion 13 of substantially the same diameter as the opening 11 and alined therewith, and an open, air inlet, front end portion 14 facing the direction of air flow through the main duct A and disposed tangentially with respect to said closed rear end portion 13. Obviously, therefore, air passing from the main duct A into and through the chamber a has a rotary or helical motion imparted thereto because of the tangential disposition of the front end portion of said chamber a relative to the rear end portion thereof.

While the auxiliary duct A' may be formed in any suitable manner, one practical manner of forming the same is first to provide the side and inner walls thereof, designated as 15 and 16, respectively, as a unit and then to rivet, weld or otherwise suitably fasten the side walls 15 at 20 their outer edges to the wall 10 of the main duct A. Thereby, the said wall 10 of the main duct A is made to serve also as the outer wall of the auxiliary duct A'.

In order to regulate the amount of air which may flow through the auxiliary duct A' to the opening 11, there is provided within the substantially semi-cylindrical rear end portion 13 of said auxiliary duct a valve designated generally as C. This valve is in the form of a substantially semi-cylindrical wall 17 which snugly fits the said substantially semi-cylindrical rear end portion 13 of the duct A' and is rotatable therein. According 25 to, by rotating said valve it obviously acts to vary the effective area of the duct A' through which air may flow from the main duct A to the opening 11. Moreover, since said valve and the rear end portion of the duct A' both are of substantially semi-cylindrical shape, it is apparent that by rotatable adjustment of said valve the auxiliary duct may be fully opened for flow of air therethrough or may be fully closed to cut off all air flow to the opening 11.

The valve C may be rotatably mounted in the duct A' in any suitable manner and any suitable means may be provided for rotatably adjusting the same. In this connection and as illustrated in the drawing, one practical manner of mounting said valve for free rotation and of providing for its convenient adjustment, is to provide the same with a stem 18 disposed axially with respect thereto; to journal the inner end portion of said stem in an opening in the inner wall 16 of the auxiliary duct A'; to journal the outer end portion of said stem in the air outlet device B; to provide either the valve or said stem with an abutment to contact the inner face of the inner wall 16 of the duct A', and to provide said stem with an abutment to engage the outer face of the said wall 16 of said duct A. The valve thus is held not only against endwise movement, but also against sidewise movement and it may therefore have a slight clearance from the side wall 15 of the duct A' whereby it may be freely and noiselessly rotated by means of a knob, handle or the like 19 on the outer end of the stem 18.

For fastening the stem 18 to the valve C the latter may be provided with radial arms, spokes or the like supporting a bearing or bearings, in which the stem 18 may be fastened, or, equivalently, and as shown the valve may be closed at its inner end by a plate 20 in the form of a segment or disk having an opening through which the stem passes and said stem may be fastened to said plate by means of a pair of nuts 21

threaded on said stem in clamping engagement with opposite faces of said plate. To permit the plate 20 to lie closely adjacent to the inner wall 16 of the duct A', the portion of said plate through which the stem 18 passes may be depressed as indicated at 22 to accommodate the innermost nut 21. Thus, either said innermost nut 21 or the plate 20 may serve as an abutment on the valve for cooperation with the inner face of the wall 16 of the duct A' to hold the valve C against endwise inward movement. On the other hand, in order to hold said valve C against endwise outward movement, a disk or washer 23 may be fastened by a screw 24 against the inner end of the stem 18 for cooperation with the outer face of the wall 16 of the duct A'.

A bearing for the front end portion of the stem 18 may be comprised either by the inner end portion 25 of the smaller or innermost flaring member 42 of the air outlet device B or by a bearing block 26 mounted in said innermost flaring member, or by both the inner end portion of said innermost flaring member and a bearing block such as the block 26 mounted therein. Alternatively, if an air outlet is not used, or if there is used an air outlet device of a different type from the device shown, a front bearing for the stem may be provided in any suitable manner. In any event, since the stem 18 is effectively journaled for free rotation, and since the valve C is, in effect, carried by said stem 18 and may, therefore, have slight clearances at all points from the auxiliary duct A', said valve C is freely, easily and noiselessly adjusted by small rotative effort exerted upon the knob or handle 19 which is exposed for finger engagement at the front of the air outlet device B.

The foregoing description and the illustration in the drawing assumes that the main supply duct is provided with a plurality of outlet openings 11. Accordingly, the auxiliary duct A' is of lesser cross sectional area than the duct A so as to lead to the opening 11 only some of the air passing through the duct A and to permit the remainder of the air passing through said duct A to reach one or more other outlet openings 11. However, the duct A may be a branch duct supplying air to only a single opening 11. In that event, the auxiliary duct may obviously be eliminated and the duct may itself be formed to lead the air to the opening 11 in the same manner as the auxiliary duct A'. In other words the duct may have the same general form as the auxiliary duct A' shown and described. In either case, the helical or rotary motion imparted to the air results in the air tending to flow laterally outward within the rounded rear end portion 13 of the duct A or A', as the case may be, and also laterally outward during its flow through and beyond the opening 11. Consequently, the delivery of the air is desirable laterally outward as well as forwardly and desirably equal in all directions laterally. Moreover, and as is apparent, air flowing through the outlet device B, if same is provided, not only is divided into separate streams and diffused, but is delivered from said device with a spiral motion whereby it becomes rapidly and thoroughly intermixed with the air of the room or the like into which it is delivered.

Preferably the opening 11 and any duct leading therefrom have greater cross sectional areas than the duct A or A', as the case may be, through which air is supplied to and through said opening. In this way there is insured a desired lessening of the velocity of the delivered air as

compared with the velocity of the supplied air even though the valve C may be fully open. However, the duct A or A', as the case may be, may have a greater cross sectional area than the opening 11 and any duct leading therefrom and adjustment of the valve C may be relied upon to obtain any desired reduction in velocity of the delivered air as compared with the velocity of the supplied air.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. Ventilating apparatus comprising a main air supply duct having an air outlet opening, and an auxiliary duct within said main duct defining a chamber through which air is required to pass in its flow from said main duct to said opening, said chamber having a closed, rounded rear end portion aligned with said opening and having an open, air inlet front end portion facing the direction of air flow through said main duct and disposed tangentially with respect to said closed rear end portion, whereby air flowing through said chamber to said opening has a helical motion imparted thereto.

2. Ventilating apparatus comprising a main air supply duct having an opening and an auxiliary duct within said main duct having a substantially semi-cylindrical closed rear end portion aligned with said opening and additionally having a portion in advance of said closed rear end portion, as regards the direction of air flow through said main duct, open at its front and disposed tangentially with respect to said closed rear end portion for cooperation with the latter to cause air flowing from said main duct to said opening to have a helical motion imparted thereto, and a substantially semi-cylindrical valve mounted in the substantially semi-cylindrical closed rear end portion of said duct for rotation to regulate the amount of air flowing through said duct to said opening.

3. Ventilating apparatus comprising a main air supply duct having an opening and an auxiliary duct within said main duct having a substantially semi-cylindrical closed rear end portion aligned with said opening and additionally having a portion in advance of said closed rear end portion, as regards the direction of air flow through said main duct, open at its front and disposed tangentially with respect to said closed rear end portion for cooperation with the latter to cause air flowing from said main duct to said opening to have a helical motion imparted thereto, said rear end portion of said auxiliary duct including a side wall and an inner wall, a substantially semi-cylindrical valve disposed in the substantially semi-cylindrical closed rear end portion of said auxiliary duct, a stem carried by said valve, and means for mounting said stem rotatably and against endwise movement in the inner wall of said auxiliary duct, thereby to mount said valve for rotation to regulate the amount of air flowing through said auxiliary duct to said opening.

4. Ventilating apparatus comprising a main air supply duct having an opening and an auxiliary duct within said main duct having a substantially semi-cylindrical closed rear end portion

aligned with said opening and additionally having a portion in advance of said closed rear end portion, as regards the direction of air flow through said main duct, open at its front and disposed tangentially with respect to said closed rear end portion for cooperation with the latter to cause air flowing from said main duct to said opening to have a helical motion imparted thereto, said rear end portion of said auxiliary duct including a side wall and an inner wall, an air outlet device mounted in air receiving relationship to said opening, a substantially semi-cylindrical valve disposed in the substantially semi-cylindrical closed rear end portion of said auxiliary duct, a stem carried by said valve, and means providing spaced journal bearings for said stem, one in the inner wall of said auxiliary duct and the other in said outlet device, thereby to rotatably mount said stem and consequently to rotatably mount said valve for rotation to regulate the amount of air flowing through said duct to said opening.

5. Ventilating apparatus comprising a main air supply duct having an opening and an auxiliary duct within said main duct having a substantially semi-cylindrical closed rear end portion aligned with said opening and additionally having a portion in advance of said closed rear end portion, as regards the direction of air flow through said main duct, open at its front and disposed tangentially with respect to said closed rear end portion for cooperation with the latter to cause air flowing from said main duct to said opening to have a helical motion imparted thereto, a substantially semi-cylindrical valve disposed in the substantially semi-cylindrical closed rear end portion of said duct, a stem carried by said valve, and means mounting said stem rotatably and against endwise movement, thereby to hold said valve against endwise movement and to mount said valve for rotation to regulate the amount of air flowing through said duct to said opening.

6. Ventilating apparatus comprising a main air supply duct having an air outlet opening, and an auxiliary duct within said main duct defining a substantially semi-cylindrical chamber axially aligned with said opening and having an open front facing the direction of air flow through the main duct, whereby part of the air flowing through the main duct is directed through said opening, and a substantially semi-cylindrical valve rotatably cooperating with said substantially semi-cylindrical chamber to regulate flow of air from said main duct through said auxiliary duct to said opening.

7. Ventilating apparatus comprising an air supply duct, walls defining the side top and bottom of said duct, said duct being of closed substantially semi-cylindrical form at one end and having at said end an opening in the bottom wall thereof, a substantially semi-cylindrical valve in said substantially semi-cylindrical end of said duct, said valve being open at its bottom and including a wall closing its top, a valve stem disposed axially of said valve and fixed thereto, said stem being journaled in the top wall of said duct for rotation, means carried by said stem and cooperating with the wall defining the top of said duct to hold said stem and valve against downward movement, and journal means for said stem fixed with respect to said duct and spaced downwardly from the journal of said stem in the wall defining the top of said duct whereby said stem and valve are held against sidewise movement

relative to the semi-cylindrical end of said duct.

8. Ventilating apparatus comprising an air supply duct, walls defining the sides, top and bottom of said duct, said duct being of closed substantially semi-cylindrical form at one end and having at said end an opening in the wall defining the bottom thereof, a valve in the said end of said duct rotatably adjustable to control flow of air through the duct into the said closed end thereof and from said closed end through the opening in said bottom wall, said valve including a curved side wall disposed closely adjacent to and concentrically with respect to the

5 curved side wall of the closed end of said duct, a stem upon which said valve is mounted, said stem being disposed axially of said valve, the wall defining the top of said duct having a bearing in which the upper end of said stem is journaled, another bearing spaced below said first mentioned bearing and fixed with respect to said duct and in which a lower portion of said stem is journaled whereby the valve is mounted for 10 rotary adjustment, and means for rotatably adjusting said valve to regulate the amount of air flowing into and from the closed end of said duct.

FRIEDRICH HONERKAMP.
